WILLIAM B. NEWLON, OF FREMONT, NEBRASKA, ASSIGNOR OF ONE-HALF TO GEORGE A. MEAD, OF CENTRAL CITY, NEBRASKA.

MILL-PRODUCT-DISCHARGING MECHANISM.

1,211,743.

Specification of Letters Patent.

Patented Jan. 9, 1917.

Application filed February 9, 1915. Serial No. 7,145.

To all whom it may concern:

Be it known that I, WILLIAM B. NEWLON, a citizen of the United States, and a resident of Fremont, in the county of Dodge 5 and State of Nebraska, have invented certain new and useful Improvements in Mill-Product-Discharging Mechanisms, of which the following is a specification.

My invention relates to mechanism for 10 controlling the discharge of mill-products, such as alfalfa-meal or the like, from chutes or bins containing such products and wherein there is maintained a certain pneumatic pressure resulting from the operation of 15 pneumatic conveyers and dust-collecting devices.

It is the object of my invention to provide a simple, inexpensive and efficient 20 means for controlling the discharge of mill-products under the described conditions, whereby the solid materials may be removed 25 from a chute or bin without permitting the escape of air therefrom in such quantity or under such pressure as to blow the pulv- 30 erulent material about and cause loss thereof or annoyance to workmen in handling the same.

A mechanism embodying my invention is 35 illustrated in the accompanying drawings, in which—

Figure 1 is a longitudinal vertical section of the mechanism on the plane of the line $x-x$ of Fig. 2, Fig. 2 is a horizontal section on the plane of the line $y-y$ of Fig. 1, 40 Fig. 3 is a detail transverse vertical section on the plane of the line $z-z$ of Fig. 1, and Fig. 4 is a perspective view with a portion of the frame broken away.

My invention is especially adapted for 45 use in mills producing alfalfa-meal, wherein the products of the milling operations are usually elevated and conveyed by pneumatic pressure, and wherein the use of dust-collectors having thick cloth screens causes 50 a comparatively heavy back-pressure of air to be constantly exerted in the bins and chutes. As a result of such air-pressure, direct removal or discharge of the dry pulv- 55 erulent material, for sacking the same, or for mixing it with other materials as in the 60 production of various stock-foods, is practically impossible because the light powdery material is blown out by the escaping air, causing loss of the material and great an-

noyance and discomfort to the workmen employed in handling the same. 55

In the illustrated embodiment of my invention I provide a rectangular casing 1, made of sheet metal, and suitably supported in a horizontal position. In the upper side 60 of said casing, at the center thereof, is an opening at which is connected the supply-chute 2, and opposite the same in the bottom of the casing there is a discharge-opening connecting with a chute 3. In the central part of the casing between the openings to the supply and discharge chutes there is a horizontal plate or partition 4 extending from side to side of the casing, and forming in the upper central part thereof a rectangular chamber 5. In said chamber there is disposed a vertical plate or head 6 which is movable horizontally in said chamber, like a piston, the extent of movement being such as to carry it in each direction past the 70 end of the supply-chute. Swingable plates 7 are pivoted on horizontal axes at the ends of the plate 4, said plates 7 being secured to rods 8 of which the ends extend through suitable bearings in the sides of the casing. 80 At one end said rods are bent laterally to form crank-like arms 9 on which weights 10 are adjustably secured, the crank-arms being in such relation to the plates 7 that the weights tend to swing the free ends of 85 the said plates up toward the top of the casing, to positions such as that shown at the right of Fig. 1.

Extending longitudinally in the lower part of the main casing is a horizontal conveyer-shaft 11 which is suitably journaled in the ends of the casing, and of which the inclosed part carries conveyer-screws 12 and 13. Said conveyer-screws are, respectively, right and left hand, so that by rotation of 90 the shaft in the proper direction said screws tend to actuate materials from the ends of the casing toward the opening to the discharge-chute 3.

Suitable actuating means for the conveyer-shaft and the movable head or piston 6, are provided as follows: Extending out from the ends of the main casing 1 is a horizontal frame 14. At one side of said frame there is journaled in suitable bearings a longitudinally extending drive-shaft 15 on which is carried a pulley 16 which is connected by a belt 17 with a suitable source of 100

power. On one end of the drive-shaft is carried a sprocket-wheel 18 and from said wheel a chain 19 extends to a sprocket-wheel 20 on the conveyer-shaft 11. The drive-shaft also carries a small bevel-gear 21 which meshes with a bevel gear 22 carried on the end of a crank-shaft 23, said shaft extending transversely across the frame and being suitably journaled therein. To the 10 piston-plate 6 there are connected rods 24 which extend horizontally through guides or packing-glands in the end of the casing, the outer end-portions of said rods being slidably supported in bearing-blocks therefor 15 on the frame. A cross-head 25 is secured to intermediate portions of the piston-rods, extending transversely between them, and from said cross-head a connecting-rod 26 extends to and is connected with the crank 20 formed by the central portion of the shaft 23. One of the swinging plates 7, that adjacent to the end of the casing through which the piston-rods extend, is slotted sufficiently to permit the piston-rods to extend 25 through it when it is in the raised position shown in Fig. 1.

In order to clearly understand the operation of the mechanism, it must be noted that the material operated upon is of a peculiar 30 consistency, and comprises a certain amount of fibrous matter formed from the stems and tougher portions of the alfalfa plant, together with a variable proportion of pulv 35 erulent material formed from the leaves and fragile portions of the plant, and of which the size of the particles ranges from that of an impalpable powder to leaf-pieces of considerable size. This material is capable of being compacted by pressure into 40 comparatively non-porous masses, and if immediately released from such pressure the material will become loose again so as to readily fall apart when a mass of considerable size is supported only at the sides or 45 edges thereof.

From the bins or other receptacles to which it is carried by the pneumatic conveying mechanism, the material descends through the chute 2 to the discharging 50 mechanism. From the chute 2 the material falls into the chamber 5 on one side or the other of the piston 6, according to the position of the piston at the time. The crank-shaft 23, through the described connections, causes the piston to reciprocate in the chamber 5 past the opening of the supply-chute, and the piston pushes the material alternately from the ends of the chamber 5 into the throat-like spaces above the 55 swinging plates 7. Said plates press yieldingly against the material causing the same to be compressed into relatively compact masses during its passage through the throat-spaces above the plates. Upon reaching 60 the outer ends of the swinging plates,

however, the pressure upon the masses of material is released and the loose material falls into the lower part of the casing at the ends thereof. From the ends of the casing the loose material is moved by the conveyer-screws to the center where it falls into the chute 3, being thereby directed to any desired point below the discharging mechanism. It will be seen that the compact masses of material in the throat-spaces 70 above the yielding plates 7 form stoppers which will effectually prevent the escape of any considerable quantity of air, which might otherwise pass down through the chute 2 along with the material from the bins. 80 The pressure exerted by the plates upon the material may be varied, as required to secure the desired effect, by adjusting the positions of the weights 10 on the crank-arms 9.

It will be obvious that various changes 85 and modifications of the described mechanism may be made without departing from the essential structure thereof, and that the mechanism may be used for discharging other products than those particularly mentioned, such as the coarser products of cereal mills, when the conditions met with are similar to those herein set forth.

Now, having described my invention, what I claim and desire to secure by Letters Pat- 95 ent is:

1. In a mechanism for discharging pulv 100 erulent materials from a receptacle containing such material together with air under pressure, a casing having a chamber 100 therein connected through an open passage with the receptacle, a reciprocating member movable in said chamber to push the material toward the end thereof, and means forming a yielding throat at the end of said chamber into which the material may be pushed directly by the reciprocating member and compacted to form a stopper for preventing escape of air from the chamber through said throat. 110

2. In a mechanism of the class described, a casing, a piston movable in said casing, means forming an open passage for directing material into the path of the piston, means forming a yieldable throat into which 115 the material may be pushed directly by the piston, and means for receiving the material discharged from the throat.

3. In a mechanism of the class described, a casing having a horizontally-extending 120 chamber therein, means for directing material into the central part of said chamber, a reciprocating piston disposed in the chamber and adapted to push material toward alternate ends thereof, there being at the ends 125 of the chamber throat-spaces into which the material is pushed by the piston, a movable plate disposed at one side of each throat-space, means connected with the plates for pressing them toward the throat-spaces to 130

5 maintain pressure upon material therein, and means for receiving material from the outer ends of the throat-spaces and conveying the same to a common discharge-opening.

4. In a mechanism of the class described, a horizontally disposed casing, a piston disposed in the upper central portion of the casing, means for reciprocating the piston horizontally, a partition-plate closing the bottom of the space traversed by the piston, a chute for directing material into the central part of the space traversed by the piston, yielding means adjoining each end of the
- 10

partition-plate and forming the lower sides 15 of throat-spaces connecting with the ends of the space traversed by the piston, and means for varying the resistance of said yielding means to displacement thereof by material pushed into the throat-spaces by the piston. 20

In testimony whereof I have hereunto subscribed my name in the presence of two witnesses.
